(57) **CLAIM**

I claim the ornamental design for a toroidal shaped particle impact damper, as shown and described.

DESCRIPTION

FIG. 1 is a perspective top view of a toroidal shaped particle impact damper, according to my new design, with a disclaimed motor shaft extending through the damper; FIG. 2 is a perspective top view of the toroidal shaped particle impact damper with a disclaimed motor shaft extending through the damper mounted onto a disclaimed printed circuit board;

FIG. 3 is a cross-sectional view of the toroidal shaped particle impact damper along line 3-3 in FIG. 1;

FIG. 4 is an exploded view of the cross-sectional side view of the toroidal shaped particle impact damper in FIG. 3;

FIG. 5 is a top cross-sectional view of the toroidal shaped particle impact damper along line 5-5 in FIG. 1.

FIG. 6 is a top planar view of the toroidal shaped particle impact damper;

FIG. 7 is a bottom planar view of the toroidal shaped particle impact damper;

FIG. 8 is a front view of the toroidal shaped particle impact damper;

FIG. 9 is a rear view of the toroidal shaped particle impact damper;

FIG. 10 is a right side view of the toroidal shaped particle impact damper; and,

FIG. 11 is a left side view of the toroidal shaped particle impact damper.

The broken lines depict features that form no part of the claimed design.
